UNITED STATES PATENT OFFICE

FREDERICK W. C. NEUNER, OF CONNERSVILLE, INDIANA, ASSIGNOR TO INDIANA LAMP CORPORATION, OF CONNERSVILLE, INDIANA, A CORPORATION

MULTIPLE PUNCHING MACHINE

Application filed September 30, 1927. Serial No. 223,016.

This invention relates to an automatic multiple punching machine which is automatic in its character by reason of its simultaneous action in moving the dies in and out of operative position in timed relation with each other, whereby it is possible to simultaneously punch a plurality of holes and emboss the metal about the flange of an article such as a lamp body or the like.

10 Heretofore, in punching holes in, or embossing the flange of an automobile lamp body or rim, or of an article of similar form, it has been customary to manually position the same over the die block for positioning 15 and supporting while the punch is rammed home, whereupon the operator would manually move the work to a new position for punching holes or forming the metal in another place. Thus, the operation of punching 20 a plurality of holes around the periphery of such an object or embossing the metal required manual manipulation and several operations.

It is the object of this invention to provide 25 an automatic punching machine which will receive such an article having an annular flange, position and secure the same, move the die blocks behind the flange and thereafter ram the embossing or punching dies home. Upon the dies being withdrawn, the 30 die blocks are moved out of engagement so as to release the work and permit its ready removal. This enables the entire process to be completed in a single operation with 35 greater accuracy.

Other features of the invention reside more particularly in the construction and operation of the die as will be hereinafter more fully set forth and described.

40 The full nature of the invention will be understood from the accompanying drawings and the following description and claims:

45 In the drawings Fig. 1 is a front elevation with a portion of the die positioning disk broken away at the top to show one of the die members, the machine being in inoperative position. Fig. 2 is the same as Fig. 1 showing the machine in operated position. 50 Fig. 3 is a side elevation showing the upper

portion in cross section illustrating the machine in inoperative position. Fig. 4 is the same as Fig. 3 illustrating the machine in operated position.

As shown herein there is a piercing jig 10 55 on the face of which there are removably secured a plurality of setting blocks 11 for supporting in proper position the work 12 to be punched. As herein illustrated, the work 12 comprises a lamp body having an inwardly 60 extending flange 13 through which it is desired to simultaneously punch a plurality of holes.

The jig is mounted upon a bolster block 14 and is operated in the usual manner 65 through the slide 15 mounted upon the usual press which is connected with the device through the connecting and operating link 16. Rotatably mounted upon the front face of the jig and supported by the shaft 17 to 70 which it is keyed, there is an actuating disk 18 provided with a plurality of cam slots 19 so formed that a portion thereof extends concentrically with the direction of rotation while another portion extends inwardly at 75 an angle thereto, for a purpose which will be hereinafter more fully set forth.

The body of the jig is provided with four keyways 20, as shown in Figs. 1 and 2, in which there are slidably mounted the punch 80 supporting blocks 21 adapted to move radially in and out with respect to the center of rotation of the disk 18. Each of said blocks 21 carries a pin 22 which extends through its respective cam slot 19 and is surrounded 85 by a roller 23. Mounted intermediate the disk 18 and each of the blocks 21 there is a die block 24 through which the pin 22 extends so as to be carried thereby in its movement conforming to the action of the disk and block 21.

90 It will be noted from the foregoing that upon rotation of the shaft 17 the disk 18 will be rotated in a counter clockwise direction 95 causing the pins 22 to follow the inclined portion of the cam slots 19 toward the periphery of the disk, thus moving the blocks 21 and the die blocks 24 carried thereon radially outward along their respective keyways 20 until they reach the position shown 100

in Figs. 2 and 4. Thus, the die block is moved into position behind the flange 13 of the work to be punched. Thereupon the continued rotation of the disk will cause the pins 22 to follow the concentric portion of the cam slots 19 so that this position is maintained during the punching operation.

The block 21 is provided with a bushing 25 through which the punch 26 extends and 25 is reciprocably mounted. Inasmuch as the die block 24 and the block 21 are connected together by the pin 22 their relative positions are constantly maintained, and the die block is provided with an opening 27 to receive the 15 punching end of the punch 26. As shown herein, the upper and lower punches are shaped to punch rectangular holes in the work, whereas the side or lateral punches are designed to punch round holes. The punch 26 is caused to slide in the bushing 25 through the forward and rearward sliding movement of the block 28 which is provided with a T-slot 29 to receive the head 30 of the punch 26. This permits of the movement of the punch 25 with respect to its operating block 28 and in conjunction with the block 21 and die block 24. The punch is moved in and out of operative position by the sliding movement of the block 28 which is actuated by the internal 30 drum 31 which is provided with cam-like recesses 32 about its periphery. A portion of said cam-like recesses extend about the periphery of the drum in a plane parallel to the face of the die, while another portion and continuation thereof extends forwardly at an angle thereto, as shown by dotted lines in Figs. 3 and 4. Mounted in the sliding block 28 there is a pin 33 which is locked in position by the lock nut 34 which extends into the 35 cam slot 32 surrounded therein by the roller 35. Thus, upon rotation of the drum 31 in a counterclockwise direction, the first part of its movement will have no effect upon the block 28 and punch by reason of the cam slot 40 extending in the parallel plane above referred to. However, upon the continuation of the rotary movement the angular direction of the slot will cause the pin 33 to force the block 28 and die forwardly into punching position.

The drum 31 is keyed to the shaft 17 which is supported at its rear end upon the bracket 36 in spaced relation to the rear face of the jig. Rigidly secured to the shaft 17 intermediate the jig and bracket 36 there is an arm 50 37 to which the link 16 is pivotally connected. Thus, upon the link being forced downwardly the arm 37 is caused to move from the position shown in dotted lines in Fig. 1 to that shown in dotted lines in Fig. 2, thus rotating the shaft to that extent. The shaft in turn likewise rotates to the same extent the drum 31 and disk 18 for actuating the die blocks and punches, as above described.

It is important to note that by reason of the arrangement of the cam slots 19 and 32, the

punches are maintained against their punching movement while the die blocks are moved radially with the punches into inoperative position, as shown in Fig. 4. Upon the continued movement of the shaft the die blocks 70 will be held against further movement in their operative position while the punches are moved forwardly to punch the work.

In operation, the work is placed between the blocks 11 when the operative parts of the 75 punch are in the positions shown in Figs. 1 and 3. Upon the downward movement of the press the disk 18 is rotated counterclockwise causing the pins 22 to be moved outwardly by the cam slots 19, thus carrying the four die 80 blocks 24 radially outwardly together with the corresponding blocks 21 and punches 26. This places the blocks directly behind the inwardly turned flange 13 of the work, as shown in Fig. 4. This may be considered as the first 85 step in the operation and comprises the first half of the downward movement of the press or rotation of the shaft.

During the continued downward movement 90 of the press or rotation of the shaft, the parts above-mentioned will retain their respective positions by reason of the pins 22 idling in the concentric portions of the cam slots 19. Also during the first step or part of the movement 95 the pins 33 will idle in the aligned portions of the slots 32 in the drum 31. Now, the pins 33 proceed in the inclined cam slots 32 so that the blocks 28 are moved forwardly to force the punches 26 through the flange 13 of the work 100 and into the openings 27 of the die head so that the punching operation is completed as illustrated in Fig. 4.

Upon the return or upward movement of the press the reverse action is obtained so that the punch 26 is first pulled rearwardly 105 to its normal position and thereafter the die blocks 24 are moved inwardly to normal position so that the work 12 may be readily removed.

From the foregoing it will be observed that 110 by one operation of the press a series of holes are simultaneously punched in the inwardly turned flange of the work. This not only obtains greater speed than heretofore, but more accuracy in the spacing thereof. While, as herein shown, there are four punches, it will be apparent that any number of punches may be employed as well as any number of die blocks. This may be obtained together with operations upon varying sizes and shapes of work by altering or changing the position of the supporting blocks 11 as well as the cam disk 18 and its associated parts.

While the invention has been described as 125 pertaining to a punch press for perforating or punching holes in the work, its application will be apparent to use in connection with other types of male and female die members for forming depressions or designs in the inwardly turned flange of the work. In this 130

connection the punch 26 may be considered as the male die member, whereas the die block 24 may be considered as the female die member.

5 The invention claimed is:

1. A device of the character described, for operating upon a piece of work having a flange extending thereabout, including a female die and a male die associated therewith, 10 means for supporting said work in relation to said dies, a cam disk adapted to move one of said dies radially during the first part of its rotation and permitting said dies to remain stationary in operating position during 15 the continued rotation thereof, a cam drum rotatable with said disk having cam slots so arranged as to be ineffective in the movement of the other die during the first part of its rotation and adapted to force the same into 20 engagement with the work during the continued rotation of said drum, and means for rotating said drum and disk first in one direction and then the other.

2. A device of the character described, for 25 operating upon a piece of work having a flange extending thereabout, including a female die and a male die associated therewith, means for supporting said work in relation to said dies, a rotatable disk having cam slots 30 therein, means on one of said dies for engagement therewith, whereby said dies will be moved radially by said disk into operative position behind said flange, a drum rotatably mounted with said disk and having a cam 35 slot therein, means associated with said other die and engaged by said cam slot for forcing said last-mentioned die into engagement with said flange, the cam slots on said disk and drum being so arranged as to cause one of 40 said dies to move while the other idles, and means for actuating said disk and drum.

3. A device of the character described, for 45 operating upon a piece of work having a flange extending thereabout, including a female die and a male die associated therewith, means for supporting said work in relation to said dies, and rotatable means having cam slots formed therein, means on said dies for engagement within said cam slots so as to be 50 actuated thereby, said slots being so arranged as to cause one of said dies to move into position behind said flange while the other die remains inoperative and thereafter cause said last-mentioned die to move forwardly into engagement therewith while the first-mentioned die remains in fixed position to receive the same.

4. A device of the character described, for 60 operating upon a piece of work having a flange extending thereabout, including a female die and a male die associated therewith, means for supporting said work in relation to said dies, a plurality of radially extending 65 keyways, die blocks slidable in said keyways

so as to move into position behind said flange for receiving the other die and thereafter move from behind said flange for permitting removal of the work, a rotatable cam member for causing said die blocks to move in and 70 out of position, means for causing the other dies to move radially so as to maintain proper registry therewith, cam means so timed with the aforementioned cam means as to move said last-mentioned dies forwardly into engagement with said flange when the aforementioned die blocks are held in operative 75 fixed position, and means for imparting rotary movement to said cam means.

5. A device of the character described, for 80 operating upon a piece of work having a flange extending thereabout, including a plurality of female dies and male dies associated therewith, means for supporting said work in relation to said dies, a plurality of radially disposed keyways formed on said device in which one set of said dies are slidably mounted, supporting members associated therewith for carrying the other set of dies in which they are transversely and slidably 85 mounted, a rotary cam member adapted to move said first-mentioned set of dies into position back of said flange and maintain the same in such fixed position during the continued rotation thereof, an actuating member 90 associated with the other set of dies for slidably moving them in said supporting member in and out of engagement with said flange, rotatable cam means for moving said last-mentioned dies into operative engagement with 95 said flange while said first-mentioned dies are held in fixed position to receive the same and maintaining them out of operative engagement while said first-mentioned dies are moved radially to and from operative position, and means for simultaneously actuating 100 said cam members.

In witness whereof, I have hereunto affixed my signature.
